UNITED STATES PATENT OFFICE.

JOHN D'ALBORA, OF YONKERS, NEW YORK.

SCOURING IMPLEMENT.

Application filed December 27, 1923. Serial No. 682,892.

The objects of this invention are to provide a device for scouring kitchen utensils and the like, which will be of simple, practical construction and which will accomplish 5 the cleaning effectively, without possibility of scratching or marring the articles operated upon.

In the accompanying drawings forming part of this specification I have illustrated 10 embodiments of the invention wherein these desired results are attained, but wish it understood that the structure may be modified in various ways without departure from the true spirit and scope of the invention as 15 hereinafter defined and claimed.

Figures 1 and 2 are front face and edge views respectively of the complete implement ready for use; Figures 3 and 4 are detail views showing the jaws of the holder 20 in open and closed positions respectively, the handle being broken away in these views; Figure 5 is a detached plan view of the sliding keeper for the spring jaws; Figures 6 and 7 are front and edge views respectively 25 of a slightly modified form of the scrubbing member; Figure 8 is a part sectional view showing another form of holder construction; Figures 9 and 10 are sectional views taken on substantially the planes of lines 9 30 and 10 of Figures 10 and 9 of a modified form of scrubber; Figure 11 is a plan view of a special reinforcement blank for the scrubber; Figure 12 is a perspective view showing this blank bent and secured in final 35 form; Figures 13 and 14 are side and sectional views respectively of the scrubber with the reinforcement secured therein.

As will be clear from the drawings the implement comprises a body 10 of scrubbing 40 material and a holder therefor. The holder is shown as consisting of a handle 11 carrying a pair of projecting spring jaws 12 having inturned cooperating pointed ends 13, and between the jaws, a projecting post 14 45 of lesser length than the jaws and terminating in a head 15 disposed inside or above the pointed jaw ends.

An inexpensive and desirable method of 50 constructing the parts last described is to make the jaws and intermediate positioning post all of a single piece of spring wire, doubled upon itself to provide a loop for the head 15 and then twisted to form the shank or post 14, the two end portions of the wire being then bent in reverse directions at 55 the upper end of the twisted shank about

a common center 16 and brought down at opposite sides of the shank to provide the opposed jaws. In the illustration these opposed jaw parts are left tensioned so as to 60 normally stand open, as in Figure 3, and a sliding keeper 17 in the form of an open elongated ring is engaged thereover for bringing the jaws together, as in Figure 4.

The handle is shown in Figures 1 and 2 as 65 constructed in two parts and the one piece jaw structure as gripped between the end portions of these parts with one of the screws, designated 16, which holds the two parts together, passed through the loop 70 formed at the upper end of the twisted shank. This construction prevents the jaws from pulling loose from the handle, as will be clear from Figure 3. A hook 18 for hanging up the device is shown as gripped 75 between the two parts of the handle and as fixed therebetween by a second screw 19 which holds together the parts of the handle at the upper end of the same.

The scouring element 10 consists of a body 80 of steel wool or the like held in the bite of the spring jaws and constructed so as to cover the jaw parts and prevent them from scratching or injuring the parts being scoured. This last effect is attained in the 85 present disclosure by making the scouring element with a reduced intermediate portion 20 by which it is gripped, and with enlargements or pads 21 at opposite sides of the same for overlying and covering the 90 gripping elements. The reduced neck may be formed by simply constricting the intermediate portion of a bundle of the steel wool and tying it so with twisted wire, as indicated at 22. To reinforce and make the 95 holding portion more solid and compact, the same may be covered by suitable wrapping such as a piece of tape, as shown at 23, in Figure 7.

The method of engaging the scrubber in 100 the holder is to slide back the keeper so as to allow the jaws to spring open, as in Figure 3, and to then bring the reduced portion of the scouring material into engagement with the head at the end of the positioning 105 post, with the points of the jaws standing at opposite sides of the reduced portion, after which the keeper is slid down over the jaws so as to force the points of the same together and into firm engagement in the compacted 110 neck portion of the material, as shown in Figure 1. Thus held, the pads 21 at the op-

posite faces of the scouring material overlap and cover the end portions of the positioning shank and holding jaws, preventing such parts from contacting with the articles 5 being scoured and allowing both faces of the scouring block or pad to be used to the greatest advantage. To facilitate getting into corners and the like, the scrubbing faces of the block may be made with substantially 10 square corners, as indicated in Figures 1 and 6, and the compacted neck portion may be of generally cylindrical form so that the block may be shifted rotatably in the holder to bring different scrubbing corners lower- 15 most as they become worn with use.

In using the implement the intermediate shank or post serves to transmit the thrust and so to a large extent relieves the holding jaws of strain, preventing them from tearing 20 the material or becoming loosened. When the scouring element becomes worn the same can be readily removed upon slipping back the keeper and permitting the jaws to spring open, after which a new element 25 may be inserted between the jaws and the jaws be brought together into holding engagement with the same by sliding the keeper back into its first position.

The twisting of the doubled portion of the 30 wire which forms the thrust shank provides in effect corrugations which operate as stops to hold the slidible keeper in the positions to which it may be adjusted over the jaws.

The holder illustrated in Figure 8 differs 35 from that previously described principally in that the central post 14 is in the form of a single rod, thickened at its end to provide the head 15 and which head is shown as formed with a longitudinal socket 24 to receive 40 the projecting twisted ends of the confining wire 22. This form of holder also provides a three-point grip on the scrubbing pad which securely holds the pad and prevents it from turning or working loose.

45 The scrubber is illustrated in Figures 9 and 10 as having annular reinforcements in the form of discs 25 secured by stitching 26 or the like to the inner faces of the working pads or heads 21. These discs are shown 50 as split in one side at 27 so that they may be easily slipped over the intermediate neck or reduced portion 20.

In Figures 11 to 14 I have shown how the reinforcement discs 25 may be made as one 55 piece joined together at one edge by an integral connecting portion 28. The two discs are folded together as shown in Figures 12 and 14 and may be secured in this relation by a tubular rivet or like member 29 which 60 surrounds the reduced neck portion of the

pad. The folded connecting portion 28 of the reinforcing discs provides in this construction a scraper more or less exposed at one edge of the pad which can be brought into use whenever necessary. 65

What I claim is:

1. A scouring implement comprising a body of scouring material having a reduced compacted portion, scouring pads at the opposite sides of the same, a holder having 70 jaws lying between the pads in engagement with such compacted portion and a post intermediate the jaws having a thrust transmitting engagement with the compacted portion. 75

2. A holder for scouring material comprising a single piece of wire doubled upon itself to form a thrust transmitting shank and having end portions doubled back from the base of said shank and directed toward 80 each other to form gripping jaws.

3. The structure of claim 2 in which the doubled end of the wire is looped to form a head and the doubled parts of the wire are twisted together to reinforce the shank. 85

4. The structure of claim 2 in which the end portions of the wire are doubled back about a common center to form concentric loops with a two-part handle engaged over the wire and having a fastening extending 90 through such loops.

5. The structure of claim 2 in which the doubled shank portion is twisted, forming corrugations and in which a slidible keeper for the jaw portions is provided and is releasably held by such corrugations. 95

6. A scouring implement comprising a body of steel wool having a reduced intermediate portion with scouring pads at the opposite sides of the same and a handle having a projecting shank bearing on top of such reduced portion and jaws engaged with opposite sides of the reduced portion, said shank and jaws projecting in between the pads and being covered thereby. 100

7. As an article of manufacture, an independent unitary body of scouring material having a scraper exposed at one edge thereof and having a reduced central portion for engagement by a gripper. 105

8. In a scouring device, a framework consisting of a tubular member having radially extending flanges at its opposite ends, pads of scouring material attached to the outer faces of the flange members, and a constricted portion of the scouring material extending through said tubular member and connecting said scouring pads. 115

In testimony whereof I affix my signature.
JOHN D'ALBORA.
